Primary Examiner — Philip S Hyder*Assistant Examiner* — Roselynne Cody(74) *Attorney, Agent, or Firm* — Foley & Lardner LLP(57) **CLAIM**

We claim the ornamental design for an axe, as shown and described.

DESCRIPTION

FIG. 1 is a front top perspective view of the claimed design; FIG. 2 is a front view of the claimed design of FIG. 1; FIG. 3 is a rear view of the claimed design of FIG. 1; FIG. 4 is a left side view of the claimed design of FIG. 1; FIG. 5 is a right side view of the claimed design of FIG. 1; FIG. 6 is a top view of the claimed design of FIG. 1; FIG. 7 is a bottom view of the claimed design of FIG. 1; and, FIG. 8 is a rear top perspective view of the claimed design of FIG. 1.

The broken lines in the drawings are for purposes of illustrating unclaimed portions of the design. Broken lines formed of equal length dashes show unclaimed portions of the design. Broken lines formed of unequal length dashes (i.e., dash-dot) show boundaries between claimed and unclaimed portions of the design.
